Pierre James
ATTORNEY

UNITED STATES PATENT OFFICE.

CHARLES W. WILLETT, OF SEATTLE, WASHINGTON.

HEADBLOCK FOR SAWMILL CARRIAGES.

1,404,820.

Specification of Letters Patent. Patented Jan. 31, 1922.

Application filed May 2, 1921. Serial No. 466,082.

To all whom it may concern:

Be it known that I, CHARLES W. WILLETT, a citizen of the United States, residing at Seattle, in the county of King and State of Washington, have invented certain new and useful Improvements in Headblocks for Sawmill Carriages, of which the following is a specification.

This invention relates to saw mill carriage head blocks; and its object is to improve the construction and efficiency of the same.

The invention consists in a head block having removable bar and wearing-plate members and to the means for reversibly mounting and securing the same in predetermined positions to the head block body member.

The invention further consists in the novel structural features and the combinations thereof as will be hereinafter described and claimed.

In the accompanying drawings, illustrating the invention in the form now preferred by me,—

Figure 1 is a transverse sectional view of a saw carriage having a head block embodying my invention. Fig. 2 is a fragmentary front elevation of the same. Fig. 3 is a perspective view of a head block bar member equipped with a wearing-plate. Fig. 4 is a detail section through 4—4 of Fig. 1.

The numeral 5 represents a saw-carriage having supporting wheels 6 which travel on track-rails 7 laid upon a mill floor.

The carriage is provided with transversely arranged head blocks such as B upon which is a knee 9 movable transversely of the carriage by means of suitable set works.

As illustrated in Figs. 1, 2 and 4, a head block comprises a hollow casting or body 8 which at opposite sides of its longitudinal axis is surmounted by removable bar members 10 which serve at 11 as guides for the knee 9.

A bar member is provided in its under side with a dovetail groove 12 to receive the correspondingly shaped upper portion 8¹ of a block body. In the top of a bar member 10 is also provided a dovetail groove 12¹ to receive a wearing-plate or rail 13 having cross section corresponding to the groove and of a thickness to protrude above the upper surface of the bar member.

The associated bar 10 and rail member 13 are secured against longitudinal displacements to a head block by means of bolts 14, 14¹ and 14² extending through holes provided in the head block and represented by broken lines 15, 15¹, and 15² in Fig. 1, to receive nuts 16 below the head block.

The foremost holes 15, one at each side of the block, are located in proximity to the front end of the same, and the central holes 15¹ are located midway between the forward and rear holes 15 and 15².

Each of the bars is provided with holes 25 in proximity of its ends 17 and intermediate thereof with holes 26 which latter are spaced to register with the body holes 15¹ and 15² when either of the holes 25 are in register with the hole 15 in either of the reversed positions of the bar in the respective groove 12.

As best shown in Fig. 3 a rail 13 is provided with two holes 18, 18¹ adjacent to its forward end 19; two holes 20, 20¹ adjacent to its rear end; and two groups of holes 21, 21¹, 21² and 22, 22¹, 22² disposed intermediate the pairs of holes aforesaid.

The holes 18, 21 and 22, moreover, are located to register with the respective bar holes and the block holes 15, 15¹ and 15² when the rail end 19 is approximately flush with the outer end as 17 of the bar.

The holes 18¹, 21¹ and 22¹ also are arranged to register with the bar and block holes when a rail has been suitably advanced.

The holes 20, 22², 21² and 20¹, 22¹, 21¹ in like manner are respectively disposed to register with the bar holes and block holes 15, 15¹ and 15² when a rail is in a position reversed to that in which it is illustrated in Fig. 1 and in one or the other of two predetermined positions longitudinally of the block.

As represented in Fig. 1 the plates or rails 13 are secured by the bolts 14, 14¹ and 14² engaging in the rail holes 18, 21 and 22.

When the outer ends of said rails become unduly worn, said bolts are withdrawn and, after shifting the rails forwardly, are inserted in the rail holes 18¹, 21¹ and 22¹ and thus secured by the respective nuts 16. With the plates thus arranged, or while removed, they are sawed or otherwise cut off to cause the forward ends of the rails to be even

with the extremities of the adjacent bar ends 19, or nearly so.

When the rails have again become worn at their front extremities they are turned 5 end for end and then employed in two positions by utilizing successively the plate holes 20, 22², 21² and 20¹, 22¹, 21, as will be understood.

When worn by the knees the bars 10 are 10 reversed to present new wearing surfaces.

Inasmuch as the bars 10 and plates or rails 13 afford in their different positions renewed bearing surfaces, the cost of maintaining the wearing or log-bearing surfaces 15 of a head block is reduced to a minimum and obviates the practice of frequently removing head blocks to a machine shop for replanning the same.

The construction, operation and advantages of the invention will be understood 20 from the foregoing description.

What I claim, is,—

1. The combination with a head block having removable knee bearing guide bars thereon, said bars having grooves in the tops thereof and provided with a plurality of spaced holes, of a wearing-plate engaging in each of said grooves, said plates being provided with series of holes arranged to 25 register with the aforesaid holes in different positions of the plates in said grooves, and bolts engageable in said holes to secure the plates in adjustable positions to the head block.

35 2. The combination with a head block having removable knee supporting members provided with longitudinally disposed dovetail shaped grooves therein and a series of spaced holes extending downwardly from 40 each of said grooves to the underside of the head block, of a wearing-plate of a dovetail shape in transverse section to fit within each of said grooves, said wearing-plates being each provided with series of holes which 45 are adapted to register with the head block holes in different positions of the wearing-plates, and bolts engaging in the holes of the head block and a selected series of the plate holes for securing the plate in various

predetermined positions longitudinally of 50 the head block.

3. The combination with a head block having a knee bearing upper portion with a dovetail shaped groove in the top thereof, of a wearing-plate adapted to fit within said 55 groove, and bolts extending through the head block for securing the plate in reverse positions and in selected positions longitudinally of the head block.

4. The combination with a head block 60 having a knee bearing upper portion with a dovetail shaped groove in the top thereof, of a wearing-plate adapted to fit within said groove, and bolts extending through the head block for securing the plate in reverse 65 positions to the head block.

5. A head block, comprising a body member, knee bearing and guide bars provided with grooves in the tops thereof, a plurality of bolts extending through said body for 70 detachably securing said bars to the body, and bearing plates provided in the respective bar grooves, said bearing plates being provided with series of holes which are arranged to receive said bolts for securing 75 the plates in different longitudinal and reversible positions with respect to said bars and the body.

6. A head block, a body member having dovetail shaped upper portions, said body 80 being provided with series of holes, knee-guiding and supporting bars provided with dovetail slots engageable with the respective upper portions of the body, each of said bars being provided with a series of holes 85 which are arranged to have some of them register with the holes of the body in reversed positions of the bars with respect to the body, and bolts extending through holes of both the body and the bars for 90 securing the latter to the body.

Signed at Seattle, Washington, this 21st day of April 1921.

CHARLES W. WILLETT.
